UNITED STATES PATENT OFFICE

152,052

DESIGN FOR A COMBINATION HANGING CORNER TOILET TISSUE CABINET AND UTILITY HOLDER

Joseph Zwart, Rockville Centre, N. Y.

Application April 29, 1947, Serial No. 138,682

Term of patent 3½ years

(Cl. D4—3)

To all whom it may concern:

Be it known that I, Joseph Zwart, a citizen of the United States, residing at Rockville Centre, L. I., in the county of Nassau and State of New York, have invented a new, original, and ornamental Design for a Combination Hanging Corner Toilet Tissue Cabinet and Utility Holder, of which the following is a specification, reference being had to the accompanying drawing, forming part thereof, in which Fig. 1 is a top plan view of a combination hanging corner toilet tissue cabinet and utility holder, showing my new design; Fig. 2 is a front elevational view; Fig. 3 is a sectional view on the line 3—3 of Fig. 2; and Fig. 4 is a fractional sectional view on the line 4—4 of Fig. 1.

I claim:

The ornamental design for a combination hanging corner toilet tissue cabinet and utility holder, as shown.

JOSEPH ZWART.
